UNITED STATES PATENT OFFICE.

JAMES E. JACKSON, OF LYNN, MASSACHUSETTS, ASSIGNOR TO UNITED SHOE MACHINERY COMPANY, OF PATERSON, NEW JERSEY, A CORPORATION OF NEW JERSEY.

INSOLE.

1,190,904.

Specification of Letters Patent.

Patented July 11, 1916.

Original application filed September 18, 1911, Serial No. 650,020. Renewed March 5, 1914, Serial No. 822,767. Divided and this application filed July 19, 1915. Serial No. 40,662.

To all whom it may concern:

Be it known that I, JAMES E. JACKSON, a citizen of the United States, residing at Lynn, in the county of Essex and State of Massachusetts, have invented certain new and useful Improvements in Insoles; and I do hereby declare the following to be a full, clear, and exact description of the invention, such as will enable others skilled in the art to which it appertains to make and use the same.

This invention relates to insoles.

More particularly the invention relates to a novel reinforced insole.

15 The insole of the present application and a machine for performing one of the steps in the process of its manufacture are disclosed in applicant's application for Letters Patent of the United States filed originally 20 September 18, 1911, Serial No. 650,020, and renewed March 5, 1914, Serial No. 822,767 (Patent No. 1,162,721, dated November 30, 1915,) from which original application this present application is a division.

25 In the early life of reinforced insoles the type having the greatest commercial success was the "Gem" disclosed in the patent to Cole No. 575,460, dated January 19, 1897. Later other types of reinforced insoles were 30 developed such as the "Economy" disclosed in the patent to Johnson No. 849,245, dated April 2, 1907, and the "Wonder - Worker" disclosed in the patent to Ryan No. 958,013, dated May 7, 1910, and to some extent in 35 the earlier patents to Krippendorf No. 579,518, dated March 23, 1897, and Bohr No. 878,453, dated February 4, 1908. The "Gem" insole was a better insole than the "Rochester" insole disclosed in the patent to 40 Moore No. 275,248, dated April 3, 1883, which preceded it, because in the Gem the reinforcing fabric is carried across the feather, thus stiffening this exceedingly flexible portion of the insole and preventing 45 its becoming curled up under the upper in the lasting and subsequent operation on the shoe. For this reason, also, the commercial supremacy of the Gem insole has been generally maintained since the introduction of

50 the Economy type of reinforced insole because this type is open to the same criticism as the Rochester insole, that is, an unrein-

forced feather is used, which is a serious defect on thin stock. At the same time the Economy insole is an improvement on the 55 Gem insole because of the greater strength of the marginal lip or rib and because the stock at both the inside and outside of the lip is of the same thickness, making for a tighter seam and for less damage to the 60 reinforcing fabric during the inseaming operation, as is well understood by those skilled in the art. Another, and a serious, defect in the Gem insole, which the later 65 types of reinforced insoles overcome, is that the duck or canvas, used as reinforcing fabric, is trimmed in such manner that its raveled edge shows beyond the edge of the insole and gives an unsightly appearance to the inside of the finished shoe. It has more 70 recently been proposed to combine some of the good features of the Economy and Gem insoles in a single insole and some manufacturers are now using an insole blank having a marginal lip or rib like that of 75 the Economy insole and a sheet of reinforcing fabric applied thereto like that of the Gem insole. An illustration of this type is found in Figure 3 of the Thoma Patent No. 1,108,026, dated August 18, 1914. 80 Still this reinforced insole, which may be termed the "Cincinnati" insole is imperfect because it does not overcome the serious defect of the fabric showing, at the shank of the insole especially, in the finished shoe. 85

The object of the present invention is to produce a reinforced insole, which overcomes all of the defects present in reinforced insoles heretofore adverted to.

To the accomplishment of this object, the 90 invention comprises an insole blank having a marginal lip or rib, reinforced with suitable fabric in the novel manner hereinafter indicated.

An understanding of the invention will 95 be assisted by reference to the accompanying drawing in which,

Fig. 1 is a transverse section across the forepart of an insole blank with its edge slit as is customary in making a Gem insole; 100 Fig. 2 is a transverse section across the forepart of the insole blank of Fig. 1 with the marginal lip upstanding and reinforcing fabric applied to its lipped face; and Fig. 3

is a transverse section across the shank of the insole of Fig. 2 after having been operated on by the present novel method.

In making the insole, the blank 2 which 5 may be of leather or any other suitable material, is preferably slit at its edge as at 4 (Fig. 1) in a plane usually parallel to the face of the blank. The section 6, on the flesh side if the blank is of leather, is then 10 upturned to form a marginal lip or rib (see Fig. 2) while the section 8, on the opposite or grain side of a leather blank, forms the feather of the insole. Reinforcing fabric 10 which is preferably, although not neces- 15 sarily, in the form of a wide sheet is then applied to the lipped face of the blank 2, being beaded or crimped about the lip or rib 6 and extending laterally to either side thereof. The fabric may be applied by 20 hand, or by any of the commercial machines supplied for performing this operation, and if applied by a machine the fabric, if it projects beyond the edge of the blank, may be simultaneously trimmed along a line coin- 25 ciding with the edge of the blank, as shown in Fig. 2. It will be understood that the reinforcing fabric, now generally used, is of the "prepared" type, that is, provided with a cementitious coating which when cool is 30 dry but which becomes tacky when heated, and it is applied to the blank while in its heated condition. The first application of the fabric seldom causes the fabric to lie snugly in the angles at the outer and inner 35 sides of the lip or rib and, therefore, a rib tightening operation on the reinforced blank is very generally performed. The machine of the parent application, from which the present application has been divided, is 40 preferably used to perform this rib tightening operation and the insole is passed through this machine while the fabric is still hot, that is, before the cementitious coating has had time to become set and hold 45 the fabric firmly to the blank. This rib tightening machine, as fully described in the present application, has tools for pressing on the fabric in the angles at both sides of the lip or rib and causing it to lie snugly 50 against the blank at these points. The rib tightening tools are also so shaped as to give the reinforced lip or rib an inward set or bend, as shown in Fig. 3 for a purpose hereinafter explained. Furthermore, this rib 55 tightening machine is provided with means to consolidate the stock at the inside of the lip or rib, forming a channel at this point, as shown at 12, (Fig. 3), and reducing the stock just inside the lip to the same thick- 60 ness as the feather. In this particular method of producing the novel insole hereinafter claimed the rib tightening tool for operating in the angle between the lip and feather, in tucking the fabric tightly into 65 the outside angle, acts to draw the fabric

slightly within the edge of the blank, as shown at 14 (Fig. 3). This is an advantageous way of removing the fabric from the marginal portion of the feather as it leaves the feather of the same thickness as 70 existed before the application of the fabric and, therefore, unweakened. In other words, the insole on completion has an un- 75 reduced feather, because in performing the last named step in its manufacture, there is 80 no reduction or thinning of any part of the feather stock. It will be obvious to those skilled in the art, however, that the use of the machine of the parent application is not essential in producing the novel insole here- 85 inafter defined by the broader claims, as any suitable or convenient means or machine may be utilized to produce the channel at the innerside of the lip or rib, to bend the lip or rib inward, or to remove the fabric 90 from the outer margin of the feather to cause its edge to lie within the edge of the blank. As a result of this method of making reinforced insoles the insole produced is possessed of all the features of advantage 95 hereinbefore adverted to, namely: the lip or rib is sufficiently strengthened, for receiving the inseam, by two layers of fabric; the stock at both sides of the lip or rib is of the same thickness, providing for a tight seam; 100 the fabric is removed from the outer margin of the feather so that it is not visible when the insole is attached to the upper; and the lip or rib is bent inwardly so as to provide a firm support for the channel guide of the 105 welt sewing machine and enable the shoe to be easily held in proper position to receive the inseam stitches.

I believe myself to be the first to produce a reinforced insole with the reinforcing fabric so applied and shaped as to render it invisible on examining the insole after having been incorporated in a shoe. The shank portion of the insole is its only portion plainly visible on looking into the completed 110 shoe and, therefore, it will be obvious that the fact that the reinforcing fabric on parts of the insole other than the shank is or is not invisible is immaterial, the true scope of the invention being found defined in the 115 appended claims.

The nature and scope of the invention having been indicated and its preferred embodiment having been specifically described, what is claimed as new, is:—

1. An insole comprising a blank provided with an upstanding marginal lip or rib, and reinforcing fabric beaded or crimped about the lip or rib and extending laterally from said lip or rib on each side thereof, the edge of said fabric at the outside of the lip or rib lying, at the shank portion of the blank at least, within the edge of the blank.

2. An insole comprising a blank provided with an upstanding, marginal lip or rib and

1. A feather outside the lip or rib, and a layer of reinforcing fabric extending across the lipped face of the blank but stopping short of the edge of the blank where it lies on the 6 feather.
2. An insole comprising a blank having a marginal lip and a feather with reinforcing fabric secured to said lip and feather, the length of the edge of the fabric on the 10 feather being less than the length of that part of the edge of the blank which is opposite the edge of the reinforcing fabric.
3. An insole comprising a blank having a marginal lip or rib and a feather of substantially even thickness throughout its width, and a sheet of reinforcing fabric secured to the lipped face of the blank, to both sides of the lip or rib and to the feather, with its 15 edge lying at the shank portion of the blank 20 at least within the edge of the feather.
4. An insole comprising a blank having a marginal lip and unreduced feather formed by slitting the edge of the blank and upturning one of the two sections thus produced, and reinforcing fabric secured across the lipped face of the insole, about the lip and across a portion of the unreduced feather its edge lying, at the shank portion 25 of the blank at least, within the edge of the 30 blank.
5. An insole comprising a blank having an inwardly bent marginal lip or rib, a feather at the outer side of the rib, a channel at the inner side of the rib, and a layer of reinforcing fabric extending across the lipped face of the blank but stopping short of the edge of the blank where it lies on the feather. 35
6. An insole comprising a blank having a marginal lip provided with a lip formed by slitting the edge of the blank 40 and upturning one of the two sections thus produced, and a channel inside the lip formed wholly by a consolidation of the insole stock, and consequent reduction in thickness, substantially to the thickness at 45 the base of the lip produced by the edge slit outside the lip.
7. An insole comprising a blank provided with an upstanding marginal rib and an unreduced feather portion outside the rib, and 50 reinforcing fabric covering the rib and extending laterally from said rib on each side thereof, but stopping short of the edge of the blank, at the shank portion at least, where it lies on the unreduced feather. 55
8. An insole comprising a blank having a marginal lip and unreduced feather formed by slitting the edge of the blank and upturning one of the two sections thus produced, a channel at the inner side of the lip, and reinforcing fabric covering the lip and extending across the channel and feather but stopping short of the edge of the blank 60 where it lies on the unreduced feather.
9. An insole comprising a blank having a marginal lip and feather formed by slitting the edge of the blank and upturning one of the two sections thus produced, and reinforcing fabric secured to the lip and extending laterally from said lip on each side thereof, the edge of the fabric where it lies on the feather stopping short of the edge of the blank, at its shank portion at least, said feather and lip being unthinned from the 65 thickness produced by the edge slit. 70
- JAMES E. JACKSON.

- 1 feather outside the lip or rib, and a layer of reinforcing fabric extending across the lipped face of the blank but stopping short of the edge of the blank where it lies on the 5 feather.
3. An insole comprising a blank having a marginal lip and a feather with reinforcing fabric secured to said lip and feather, the length of the edge of the fabric on the 10 feather being less than the length of that part of the edge of the blank which is opposite the edge of the reinforcing fabric.
4. An insole comprising a blank having a marginal lip or rib and a feather of substantially even thickness throughout its width, and a sheet of reinforcing fabric secured to the lipped face of the blank, to both sides of the lip or rib and to the feather, with its 15 edge lying at the shank portion of the blank 20 at least within the edge of the feather.
5. An insole comprising a blank having a marginal lip and unreduced feather formed by slitting the edge of the blank and upturning one of the two sections thus produced, and reinforcing fabric secured across the lipped face of the insole, about the lip and across a portion of the unreduced feather its edge lying, at the shank portion of the blank at least, within the edge of the 25 blank.
6. An insole comprising a blank having an inwardly bent marginal lip or rib, a feather at the outer side of the rib, a channel at the inner side of the rib, and a layer of reinforcing fabric extending across the lipped face of the blank but stopping short of the edge of the blank where it lies on the 30 feather.
7. An insole blank provided with a lip formed by slitting the edge of the blank and upturning one of the two sections thus produced, and a channel inside the lip formed wholly by a consolidation of the insole stock, and consequent reduction in thickness, substantially to the thickness at the base of the lip produced by the edge slit outside the lip.
8. An insole comprising a blank provided with an upstanding marginal rib and an unreduced feather portion outside the rib, and reinforcing fabric covering the rib and extending laterally from said rib on each side thereof, but stopping short of the edge of the blank, at the shank portion at least, where it lies on the unreduced feather.
9. An insole comprising a blank having a marginal lip and unreduced feather formed by slitting the edge of the blank and upturning one of the two sections thus produced, a channel at the inner side of the lip, and reinforcing fabric covering the lip and extending across the channel and feather but stopping short of the edge of the blank where it lies on the unreduced feather.
10. An insole comprising a blank having a marginal lip and feather formed by slitting the edge of the blank and upturning one of the two sections thus produced, and reinforcing fabric secured to the lip and extending laterally from said lip on each side thereof, the edge of the fabric where it lies on the feather stopping short of the edge of the blank, at its shank portion at least, said feather and lip being unthinned from the thickness produced by the edge slit.

JAMES E. JACKSON.

Correction in Letters Patent No. 1,190,904

It is hereby certified that in Letters Patent No. 1,190,904, granted July 11, 1916, upon the application of James E. Jackson, of Lynn, Massachusetts, for an improvement in "Insoles," an error appears in the printed specification requiring correction as follows: Page 2, line 47, for the word "present" read *parent*; and that the said Letters Patent should be read with this correction therein that the same may conform to the record of the case in the Patent Office.

Signed and sealed this 22d day of August, A. D., 1916.
